Theodore D. Kline INVENTOR

BY *Munn G.*

ATTORNEYS

UNITED STATES PATENT OFFICE.

THEODORE D. KLINE, OF SAVANNAH, GEORGIA.

EXHAUST MECHANISM.

SPECIFICATION forming part of Letters Patent No. 701,204, dated May 27, 1902.

Application filed October 5, 1901. Serial No. 77,681. (No model.)

To all whom it may concern:

Be it known that I, THEODORE D. KLINE, a citizen of the United States, residing at Savannah, in the county of Chatham and State of Georgia, have made certain new and useful Improvements in Exhaust Mechanism, of which the following is a specification.

My invention is an improvement in exhaust mechanism for use on locomotives; and the invention consists in certain novel constructions and combinations of parts, as will be hereinafter described and claimed.

In the drawings, Figure 1 is a side elevation of the exhaust mechanism embodying my invention. Fig. 2 is a longitudinal section thereof on about the line 2 2 of Fig. 3. Fig. 3 is a longitudinal section of the mechanism on about the line 3 3 of Fig. 2. Fig. 4 is a longitudinal section similar to Fig. 3, but showing the valve adjusted to open the auxiliary exhaust-flue. Fig. 5 is a top plan view of the mechanism. Fig. 6 is a cross-sectional view on about line 6 6 of Fig. 2. Fig. 7 is a cross-sectional view on about line 7 7 of Fig. 3. Fig. 8 is a cross-section on about line 8 8 of Fig. 3, and Fig. 9 is a cross-sectional view on about line 9 9 of Fig. 3.

In practice the exhaust mechanism in the form of a regulator occupies the same position in the smoke-box of a locomotive as the ordinary exhaust-pipe now in use, and I form the body A of the regulator by means of a central partition A' with side flues A², to which the exhaust from the opposite cylinders is delivered by pipes in any suitable manner. By preference I form the body A of the regulator of a cylindrical casing a, which is divided longitudinally by the partition A', and such casing is preferably tapered toward its upper end, where it delivers to the confluent chamber B, whose upper end is in communication with the main exhaust-flue C and the auxiliary exhaust-flue D, communication with the flue D being controlled by the valve E, which valve is arranged to operate in a lateral extension B' of the chamber B and for adjustment, as shown in Fig. 3, to cut off the auxiliary flue D or, as shown in Fig. 4, to open the communication between the chamber B and the flue D whenever it is desired to give the maximum or minimum draft on the fire.

The valve E is hinged at E', so it can be turned from the position shown in Fig. 3 to that shown in Fig. 4, and vice versa, and is secured upon a shaft F, which may be provided with a crank-arm and connected with a suitable operating-lever in the cab of the engine, which may be operated to adjust the valve to any desired position, and suitable detent devices may be provided for securing the valve in any position to which it may be adjusted.

It will be noticed from Fig. 9 that the lower portion of the body A of the device is circular in cross-section and from Fig. 8 that the form of the body of the regulator at its upper end is rectangular, which is also the form of the chamber B, which may be termed a "confluent" or "intermediate" chamber. It will also be noticed from Fig. 7 that the cross-section of the regulator at the lower end of the main and auxiliary exhaust-flues is rectangular, affording a square seat for the swinging edge of the valve E, and that the upper portion of the regulator gradually assumes a circular form in cross-section, as will be understood from Figs. 5 and 6.

In forming the regulator I find it desirable to cast the body A, the exhaust-flues C and D, and the front and rear plates b and b' of the intermediate chamber B in one piece, and to close the sides of the chamber B by the side plates G, which may be suitably bolted in place, as shown in Figs. 1, 2, and 5, and will operate to inclose the valve and direct the exhaust to the flues.

In supporting the shaft F, I extend it at f at one end beyond the side edge of the valve, so it can have a bearing in a boss F' on one of the side plates G, the other end of the shaft being extended through a stuffing-box at f², so it can be connected with the operating devices, as desired. The side plates G are planed on their inner faces and the outer edges of the regulator are also planed to receive the said side plate, making a steam-pipe joint when the plates G are bolted in place. In Fig. 3 I show the valve E adjusted to close the auxiliary opening or flue D, which causes all of the exhaust to pass out of the main flue C, which gives the maximum draft on the fire. This Fig. 3 also shows the change of form of the regulator, where it gradually

changes from a square or rectangular cross-section at line 77 to a circular cross-section at its upper end.

In Fig. 4 the valve is shown adjusted to 5 open the auxiliary flue D and permit the steam to pass out of the opening d into the flue D, which gradually enlarges circumferentially toward the upper end of the regulator. When this flue D is open, the exhaust is 10 relieved of considerable back pressure, as will be readily understood by those skilled in the art.

It will be noticed from the drawings and 15 the foregoing that the flues C and D form at their upper ends concentric nozzles for the discharge of the exhaust-steam, the main flue C being centrally within the flue D at the upper end of the latter, and the said flue D encircling the flue C at its upper end and 20 gradually reducing toward its lower end, where it opens at d to one side of the main flue C, as shown.

Having thus described my invention, what 25 I claim as new, and desire to secure by Letters Patent, is—

1. In an exhaust mechanism for locomotives, the combination with a main exhaust-flue, of an auxiliary exhaust-flue opening at its lower end at one side of the main flue and 30 gradually enlarging circumferentially around said main flue above its lower inlet end, and means controlling the auxiliary flue, substantially as set forth.

2. The combination in an exhaust mechanism 35 substantially as described, of a main exhaust-flue, and a side exhaust-flue opening at its lower end laterally to the main flue and gradually widening circumferentially above said opening, substantially as set forth.

3. The combination of the main exhaust-flue, the supplemental or auxiliary exhaust-flue arranged alongside the main flue and encircling the same at its upper end and gradually reducing to an opening lateral to the 45 main flue at the lower end of the auxiliary

flue whereby there are provided two concentric nozzles at the upper end of the regulator and a reduced auxiliary flue-opening at the lower end of the main flue, and a valve controlling the auxiliary exhaust-flue, substantially as set forth.

4. The combination in an exhaust mechanism of the main or body portion, the intermediate chamber, the exhaust-nozzles above the said chamber and in communication at 55 their lower ends therewith, said nozzles being composed of an inner or central nozzle and an outer nozzle encircling the inner nozzle at its upper end and gradually reducing toward its lower end and opening at said end 60 laterally to the inner nozzle, and a valve controlling the lower end of the auxiliary nozzle, substantially as set forth.

5. An apparatus substantially as described comprising the main or body portion circular 65 in cross-section, the intermediate chamber rectangular in cross-section and extending laterally beyond the circumference of the body portion, the main flue in line with the body portion, the supplemental or auxiliary 70 flue having a circular upper portion encircling the orifice of the main flue and gradually narrowing thence toward its lower end and communicating at such end with the upper end of the lateral extension of the intermediate chamber, and the valve controlling the lower end of the supplemental flue, substantially as set forth.

6. An exhaust mechanism comprising the main flue, the supplemental or exhaust flue, 80 encircling the main flue at its upper end and having an inlet-opening at its lower end and gradually converging or narrowing from its upper circular portion toward such inlet-opening substantially as set forth.

THEODORE D. KLINE.
